UNITED STATES PATENT OFFICE.

JOHN D. MCFARLAND, OF ST. LOUIS, MISSOURI.

POWDER BOX.

Application filed November 12, 1921. Serial No. 514,506.

To all whom it may concern:

Be it known that I, JOHN D. MCFARLAND, a citizen of the United States of America, residing at the city of St. Louis, State of Missouri, have invented a certain new and useful Powder Box, of which the following is such a full, clear, and exact description as will enable any one skilled in the art to which it appertains to make and use the same, reference being had to the accompanying drawings, forming part of this specification.

Boxes for containing face powder are usually made of paper in cylindrical form, the box being composed of a body and lid telescoping together and the lid usually being domed to enhance the appearance of the box. It has been found in practice that it is impossible to produce such a box in which the fit between the lid and body will be sufficiently tight to prevent the escape of the contents. This difficulty is increased by the domed form of the lid as this causes the box to act as bellows when pressure is applied to the lid thus forcing air out of the box and carrying powder with it.

As far as I am aware the only effective form of box for overcoming this difficulty is what is known as a drum box in which a thin piece of paper is pasted over the top of the box body. This construction necessitates the filling of the box from the bottom, the base of the box being afterwards pasted in position. Not only is this process expensive but such a box is effective only when in transit or in the hands of the dealer, for as soon as the thin paper is removed, which it is necessary to do to reach the contents of the box, the effectiveness of the box is destroyed so that in the hands of the user it has the same objection as the ordinary form of box.

It is the object of my invention to provide a simple and inexpensive box in which the aforesaid difficulties are overcome so that the box may be filled in the usual manner and will prove effective in preventing the escape of powder not only when the box is in transit and in the hands of the dealer but also when in the hands of the user.

In the accompanying drawings which illustrate some forms of boxes made in accordance with my invention, Figure 1 is a vertical central section on a slightly reduced scale; Figure 2 is a bottom plan view of the lid; Figure 3 is a vertical section through

one side of a box showing a slight modification and Figure 4 is a view similar to Figure 3 showing a further modification.

5 indicates the body of my box which is 60 cylindrical in form and made of paper. This box body 5 is provided with an upwardly extending flange 6. 7 is a lid of the box provided with a downwardly extending flange 8 of such size as to telescope with the flange 6 65 in the usual manner. The lid 7 may be either domed as shown in Figures 1 and 3 or flat as shown in Figure 4.

In carrying out my invention, I provide the lid 7 with what I term a reinforcing 70 member, which member forms, together with flange 8, a V-shaped annular groove into which the upper edge of the flange 6 is forced to form an impervious joint. This reinforcing member consists in a disc 9 having a beveled edge 10. The large diameter of this disc 9 is equal to the internal diameter of the flange 8 so that the disc is accurately seated in the lid concentric with the flange when it is placed in position. The small diameter of the disc is somewhat less than the internal diameter of the flange 8 so that the V-shaped groove thus formed will receive the said flange 6 when the cover is placed in position on the box.

The disc 9 may be made of any suitable material but I prefer to make it of that class of card board known in the trade as pulp board, as such board is slightly yielding in character and assists in the forming of an impervious joint. The disc 9 may be applied to the lid by pasting it directly to the outer edge of the domed top as shown at 11 (Figure 3) or in case the top is not domed it may be placed against the entire 90 lower face of the lid as shown in Figure 4. I prefer, however, when the lid is domed to provide it with an annular spacing member 12, shown in Figure 1, which member is pasted against the inner face of the upper 95 part of the lid and provides an annular ledge against which the disc 12 may be pasted, thus not only providing a flat and level surface against which to secure the disc 9 but also enabling users of the present 100 form of drum box to substitute a box of my construction which will contain the same amount of powder without decreasing the size of the box and thus the apparent amount of powder sold.

When the lid of my box is placed in position upon the box body, the upper edge

of the flange 6 will be forced between the converging sides of the annular V-shaped groove formed between the beveled edge of the disc 9 and the flange 8 thus compressing 5 the upper edge of the flange 6 and securing an impervious joint, which action is assisted by the yielding nature of the disc 9. It will be evident therefore that my box will prevent the escape of the powder not only 10 during transit and in the hands of the dealer but will be equally effective in the hands of the user.

While I have described my box as cylindrical in form, I wish it to be understood 15 that I do not wish to limit myself to such form except where specifically stated in the claims as the box may be made square, oval or any other suitable form.

Having fully described my invention what 20 I claim as new and desire to secure by Letters Patent of the United States is:

1. In a device of the class described, the combination with a box body having an upwardly extending flange, of a lid having a 25 downwardly extending flange telescoping with said first named flange, and a member forming with one of said flanges a V-shaped groove into which the other of said flanges is adapted to be forced to form an impervious joint.

2. In a device of the class described, the combination with a box body having an upwardly extending flange, of a lid having a downwardly extending flange surrounding 35 said first named flange, and a re-inforcing member in said lid forming with the flange thereon a V-shaped groove into which the flange on the box body is adapted to be forced to form an impervious joint.

3. In a device of the class described, the combination with a box body having an upwardly extending flange, of a lid having 40 downwardly extending flange telescoping

with said first named flange, and an internal re-inforcing member having a beveled edge 45 and forming with one of said flanges a V-shaped groove into which the other of said flanges is adapted to be forced to form an impervious joint.

4. In a device of the class described, the combination with a cylindrical box body having an upwardly extending flange, of a lid for said body having a downwardly extending flange surrounding said first named flange, and a disc secured in said lid 55 and forming with the flange thereon a V-shaped annular groove adapted to receive the flange on the body and to form therewith an impervious joint.

5. In a device of the class described, the combination with a cylindrical box body having an upwardly extending flange, of a lid for said body having a downwardly extending flange surrounding said first named flange, and a disc having a beveled edge, said 65 disc being secured in said lid and forming with the flange thereon a V-shaped annular groove adapted to receive the flange on said body and form therewith an impervious joint.

6. In a device of the class described, the combination with a cylindrical box body having an upwardly extending flange, of a lid for said body having a downwardly extending flange surrounding said first named flange, an annular spacing member in said lid, and a disc provided with a beveled edge, said disc being situated in said lid and secured against the lower edge of said spacing member, whereby an annular V-shaped groove is formed between said disc and flange to receive the flange on the box body and to form therewith an impervious joint.

In testimony whereof, I have hereunto set my hand and affixed my seal.

JOHN D. McFARLAND. [L. s.]
